UNITED STATES PATENT OFFICE.

EDWIN S. VOTEY, OF SUMMIT, NEW JERSEY, ASSIGNOR TO THE AEOLIAN COMPANY, OF NEW YORK, N. Y., A CORPORATION OF CONNECTICUT.

MECHANICAL MUSICAL INSTRUMENT.

No. 826,754.

Specification of Letters Patent.

Patented July 24, 1906.

Application filed December 1, 1905. Serial No. 289,762.

To all whom it may concern:

Be it known that I, EDWIN S. VOTEY, a citizen of the United States, and a resident of Summit, in the county of Union and State 5 of New Jersey, have invented certain new and useful Improvements in Mechanical Musical Instruments, of which the following is a specification.

My invention relates to mechanical musical instruments, and particularly to pianos having horizontally-disposed case and strings, such as grand or square pianos. Its object is to provide such pianos with means for playing them pneumatically controlled by 15 a perforated music-sheet without considerably or disagreeably changing the appearance of the piano and without interfering in any way with its manual operation.

It consists of means to these ends and of 20 combinations of parts, which will be pointed out in the claims.

In the drawings, Figure 1 is a front elevation of so much of a keyboard musical instrument as is necessary to illustrate my invention. Fig. 2 is a vertical section through the line 2 2, Fig. 1.

1 designates the bottom of an instrument, above which are mounted keys 2, which 30 keys together constitute the keyboard of the instrument. The mechanism by which these operate on the strings 3 is not shown, as it forms no part of the present invention.

Mounted above the keyboard of the instrument and somewhat at the rear of the 35 manual portion thereof, and in the present instance above the forward ends of the strings 3 and directly overlying the front portion of the frame 31 of the instrument to which said forward ends of the strings are 40 secured, is a portion of the pneumatic playing apparatus comprising a music-sheet-winding roll 4, commonly known at a "take-up roll," a tracker 5, over which the music - sheet passes, supports 6 and 7 for the music-sheet, 45 one of which, 6, is a driving-shaft by which the roll may be rewound in the usual manner, and a series of pneumatic bellows 8 for rotating the winding-roll 4 and the driving-shaft 6 of the music-support. The actuating 50 mechanism 8 is connected by means of the shafts and gears (shown in Fig. 1 of the

drawings) for operating the winding-roll and the driving-shaft. As these form no part of the present invention and may be modified as desired, it is not necessary to here 55 further describe them. From the tracker 5 and connected with each of the ducts 9 thereof is a flexible connection 10, which in the present instance leads below the keyboard 2 and below the bottom 1 of the instrument to a pneumatic action, consisting 60 ordinarily of primary, secondary, and striking pneumatics, which, as they form no part of the present invention, are not herein shown. 65

It is evident that certain modifications may be made in the device without departing from the spirit of the invention.

What I claim is—

1. In a piano, a horizontally-disposed case 70 and strings, a keyboard, and a winding-roll, a tracker and a music-sheet support mounted above said keyboard and said strings and overlying the front portion of the string-supporting frame. 75

2. In a piano, a horizontally-disposed case and strings, a keyboard, and a winding-roll, a tracker, a music-sheet support and pneumatic mechanism for rotating said winding-roll mounted above said keyboard and above 80 said strings and overlying the front portion of the string-supporting frame.

3. In a piano, a horizontally-disposed case and strings, a keyboard, and a winding-roll, a tracker, a music-sheet support and pneumatic mechanism for rotating said winding-roll mounted above said keyboard and said 85 strings and overlying the front portion of the string-supporting frame, said pneumatic mechanism being located at one side of said 90 winding-roll, tracker and music-sheet support.

4. In a piano, a horizontally-disposed case and strings, a keyboard, a winding-roll, a tracker and a music-sheet support mounted 95 above said keyboard and said strings and overlying the front portion of the string-supporting frame, and connections leading from said tracker to a point beneath said keyboard. 100

5. In a piano, a horizontally-disposed case and strings, a keyboard, a winding-roll, a

tracker and a music-sheet support mounted above said keyboard and said strings and overlying the front portion of the string-supporting frame, and connections leading 5 from said tracker to a point beneath the bottom of said case.

In testimony whereof I have signed this

specification in the presence of two subscribing witnesses.

EDWIN S. VOTEY.
